PIPE CUTTER

Filed Nov. 3, 1934

UNITED STATES PATENT OFFICE

2,109,688

PIPE CUTTER

Walter L. Church, Houston, Tex.

Application November 3, 1934, Serial No. 751,277

12 Claims. (Cl. 164—0.8)

This invention relates to a pipe cutter.

An object of the invention is to provide an inside pipe cutter of the type adapted to cut by rotation and embodying novel means for maintaining the cutters in active or inactive positions.

Another object is to provide in a pipe cutter, novel means for maintaining the cutter blades in inactive position while lowering the cutter into the pipe or relocating the same therein, said means being releasable by a rotation of the operating string and being capable of reengagement by longitudinal movement of the operating string to the end that it will not be necessary to rotate said string to the left and to thereby incur the risk of unscrewing a joint connecting sections of said string.

This invention embodies certain improvements over that type of inside pipe cutter disclosed in the application filed by myself and others in the United States Patent Office on the 14th day of September, 1931, under Serial Number 562,768, issued May 15, 1934, under Patent No. 1,959,284, as well as that type disclosed in application filed by myself on March 27, 1934, under Serial Number 717,570.

With the above and other objects in view, this invention has particular relation to certain novel features of construction, operation and arrangement of parts, an example of which is given in this specification and illustrated in the accompanying drawing, wherein:

Figure 1 shows a side view of the cutter, partly in section, shown in inactive position and located in the pipe to be cut.

Figure 2 shows a similar view to that shown in Figure 1 showing the cutter in active position.

Figure 3 shows a cross sectional view taken on the line 3—3 of Figure 2, and

Figure 4 shows a fragmentary side view of the operating stem showing a type of pipe puller to be used for pulling the cut pipe.

Referring now more particularly to the drawing wherein like numerals of reference designate the same parts in each of the figures, the numeral 1 designates the tubular cutter body which may be attached to the lower end of the operating string 2 and which is reduced and extended forming the tubular mandrel 3. Attached to the lower end of the mandrel there is a suitable guide 4. The lower end of the body proper has the external blade slots 5 wherein are pivoted the swinging blades 6. The upper ends of these blades are extended above their pivots and are seated against the outwardly working springs 7 in the body

which normally hold the blades retracted. The lower ends of the blades have the outwardly directed points, or bits, 8. Any suitable type of blades or cutters may be employed.

On the mandrel beneath the cutter body there is a wedge ring 9 whose upper end is formed with the upwardly extended, wedge like blade actuators 10 having the external downwardly flared faces 11 and the blades have the correspondingly beveled inside faces 12 which may ride on the faces 11 to expand the blades. The ring 9 is suitably splined on the mandrel 3.

On the mandrel beneath the wedge ring 9 there is a jaw expander 13, having the upper and lower upwardly flared faces 14, 14'. The adjacent ends of the ring 9 and expander 13 have the internal annular grooves 15, 16, respectively and there is an inside coupling ring 17 having the outside ribs 18, 19 which run in said grooves whereby the wedge ring may turn relative to the expander 13. A suitable bearing ring 20 may be interposed between said wedge ring and expander if desired.

The expander 13 has the tubular extension 21 which fits loosely over the mandrel 3 and a sleeve like liner 22 has a sliding fit on said extension. Around the expander 13 and the extension 21 thereof there is a sleeve 23 into which the liner 22 is driven and in the lower end of which are mounted the radial gripping members 24 which are seated on the coil springs 25. The inner ends of said springs rest against said liner. The ends of said gripping members engage the heads of the set screws 26 which are screwed into the sleeve 23. The guide 4 and sleeve 23 may be connected by the slips 27, more accurately shown in Figure 2. These slips have the outside, downwardly tapering faces 27a which ride against corresponding, inside downwardly converging faces 27b, in the lower end of the sleeve 23. They have the inside right hand buttress threads 27c to receive corresponding threads 4a on the reduced upper end of the guide 4. The slips are normally held in their downward and inward position by the action of gravity, which may be assisted by springs 27d which are interposed between the upper ends of the slips and the downwardly facing shoulder 23a of the sleeve 23.

Mounted in the upper end of the sleeve 23 are the radially movable slip jaws 28 whose inner sides have the tapering upper and lower faces 29, 29' which conform to the shape of and ride against the faces 14, 14'. The outer surfaces of these slip jaws are toothed. These jaws work through suitable slots in the sleeve 23 and their ends engage the heads of set screws 30, screwed

into said sleeve, whereby the jaws are retained in place.

When the guide 4 is screwed into the slips 27, as shown in Figure 1, the springs 21d will operate 5 to hold the slips in their downward and inward position and the threads 27c are upwardly pitched and the corresponding threads 4a are downwardly pitched so that guide 4 will be securely held by said slips and the cutter will be maintained in 10 inactive position.

In operation the cutting tool, as shown in Figure 1, is lowered into the pipe to be cut to the point selected for the cut. The gripping members 24 are in frictional engagement with the 15 inside of the pipe and when the tool is located at the selected place the operating string 2 and the mandrel 3 may be turned to the right and meanwhile lowered and the guide 4 will be gradually screwed out of and detached from the slips 20 27 and the lower end of the sleeve 23, said gripping members meanwhile holding said sleeve stationary.

The mandrel 3 and expander 13, may then move downwardly relative to the slip jaws and 25 said jaws will be expanded into engagement with the pipe to be cut and the tool will thereby be anchored in place and the blades will be actuated outwardly by the actuators 10 into engagement with the inside of the pipe. The operating string 30 may now be rotated and gradually lowered and the blade bits 8 will be gradually forced outwardly until the pipe is severed.

The string 2 and mandrel 3 may now be elevated and the reduced upper end of the guide 35 4 will enter between the slips 27, said slips moving upwardly and outwardly to permit this, and thereupon the threads 4a and 27c will interengage and the guide 4 may thus be reattached to the sleeve 23 without the necessity of turning the 40 string to the left and incurring the danger of unscrewing a joint connecting the sections thereof.

When the guide is reattached to the sleeve 23, the expander 13 will be maintained in its upper, 45 or released, position to release the jaws 28 and said jaws may then move inwardly to release the pipe. The body 1 will also have moved upwardly to carry the blades 6 clear of the blade actuators and the blade bits will be retracted by the springs 50 7 to clear the cut off section of the pipe.

The tool may then be lowered to carry the grapple, or fishing tool 35, carried by the operating string, down into the cut off section to pull the same from the well, if the same can not be 55 pulled, the cutting tool may be relocated therein and another cut made.

What I claim is:

1. A pipe cutter adapted to cut a pipe in a well by rotation, and comprising relatively movable parts, means for gripping the pipe to be cut and effective to hold one of the parts stationary, the other part being also rotatable relative to the stationary part, a tapering face on one part, a wedge shaped slip mounted to cooperate with said face under the influence of gravity and radially movable and having threads, the other part having threads arranged to engage the slip threads and to be disengaged therefrom by rotation to permit the downward movement of one part, relative to the other part, upon disconnection with said threads, a cutter on the rotatable part, means for actuating the cutter outwardly into cutting relation with the pipe upon such downward movement, said slip being movable radially 70

upon upward movement of the rotatable part to permit the inter-engagement of said threads.

2. A pipe cutter adapted to cut a pipe in a well by rotation, and comprising relatively movable parts, means for gripping the pipe to be cut and effective to hold one of said parts stationary, the other part being also rotatable relative to the stationary part, a slip movably mounted on one part and movable to active position under the influence of gravity and having threads, the other part having threads arranged to engage the slip threads and to be disengaged therefrom by rotation of the rotatable part to permit downward movement of the rotatable part upon disconnection of the threads, a cutter on the rotatable part, means for actuating the cutter outwardly into cutting relation with the pipe upon such downward movement, said slip being movable radially upon non-rotative upward movement of the movable part to permit the threads to pass and to interengage upon completion of such upward movement to hold said movable part in upper or elevated position.

3. A pipe cutter adapted to cut a pipe in a well by rotation and comprising two parts which are relatively movable longitudinally, means for gripping the pipe to be cut and effective to hold one of said parts stationary, the other part being also rotatable relative to the stationary part, a movably mounted slip on one part having threads and movable to active position under the influence of gravity, the other part having threads formed to mesh with the slip threads when the slip is in active position and to be disengaged therefrom by rotation of the rotatable part, whereby to permit downward movement of the rotatable part upon disconnection of the threads, cutting means movable outwardly into cutting relation with the pipe upon such downward movement, said slip being mounted to move approximately radially upon a non-rotative, upward movement of the rotatable part to permit cooperating threads to assume their intermeshed engagement to hold said movable part in upper or elevated position.

4. A pipe cutter adapted to cut a pipe in a well by rotation and comprising two parts which are relatively movable longitudinally, means for gripping the pipe to be cut and effective to hold one of said parts stationary, the other part being also rotatable relative to the stationary part, a movably mounted slip on one part subject to movement by gravity and having threads, the other part having threads formed to mesh with the slip threads upon gravity movement of the slip and to be disengaged therefrom by rotation of the rotatable part, whereby to permit downward movement of the rotatable part upon disconnection of the threads, cutting means movable outwardly into cutting relation with the pipe upon such downward movement, said slip being mounted to move approximately radially upon a non-rotative, upward movement of the rotatable part to permit cooperating threads to assume their intermeshed engagement to hold said movable part in upper or elevated position, and means for limiting the range of longitudinal movement of the rotatable part relative to the stationary part.

5. A pipe cutter adapted to cut by rotation in a pipe in a well and comprising a tubular cutter body having vertical slots, a tubular mandrel formed integrally with and depending from the body, cutters pivotally mounted in said slots whose lower ends are provided with outwardly 75

- directed bits and inside beveled faces, a wedge ring on the mandrel beneath the cutters formed with cutter actuators, means preventing the rotation of the ring relative to the mandrel, a tubular jaw expander on the mandrel having upwardly flared faces, means for rotatably connecting the expander with the wedge ring, a tubular extension depending from the expander around the mandrel, a sleeve around said extension, upwardly and outwardly expansible slips in the sleeve normally held in contracted position by gravity, yieldably mounted gripping members on said sleeve, a guide attached to the lower end of the mandrel, said guide and slips having intermeshing threads having a wedging engagement, shaped to effect the expansion of the slips and engagement of the threads upon a longitudinal movement of the mandrel and guide relative to the sleeve and to be disconnected by rotation of the mandrel and guide relative to the sleeve and slip jaws mounted on the sleeve and arranged to be expanded by said expander upon release of the guide from the sleeve.
6. A pipe cutter adapted to be cut by rotation in a well and comprising a tubular cutter body whose lower end is reduced and extended forming a tubular mandrel, said body having vertical side slots above the mandrel, cutters in said slots whose upper ends are pivoted and whose lower ends are formed with outwardly directed bits, yieldable means normally holding the bits retracted, a guide attached to the lower end of the mandrel, a wedge ring splined on the mandrel beneath the cutter body and having inwardly tapering actuators thereon, said cutters having beveled inside faces adapted to ride on said actuators to expand the cutters, a jaw expander having a downwardly tapering face and located on the mandrel beneath the wedge ring, means connecting the expander and wedge ring to permit their relative rotation, a tubular extension on the expander around the mandrel, a sleeve around said extension having a downwardly converging face, radially movable gripping members working through said sleeve, yieldable members normally holding said gripping members outwardly, slip jaws mounted in the sleeve around the expander, expansible slips on said face, the downward pitch of the face being such that the slips will be normally held in contracted position by gravity, said guide and slips having threads shaped to expand the slips and intermesh the threads upon longitudinal movement of the guide relative to the sleeve in one direction, and shaped to be released by rotation of the mandrel and guide, relative to the sleeve.
7. A pipe cutter adapted to cut a pipe in a well by rotation and comprising relatively movable parts, means for gripping the pipe to be cut and effective to hold one of said parts stationary, an upwardly and outwardly tapering face on the stationary part, a wedge shaped slip mounted on said face to move upwardly and outwardly in the stationary part, threads on the slips and the other part whereby said parts may be connected and disconnected, said threads being shaped to be engaged upon the upward movement of said other part and to be disengaged by the rotation of said other part, said rotatable part being movable downwardly relative to the stationary part when the threads are disconnected, a cutter on one part and means for actuating the cutter outwardly into cutting relation with the pipe upon such downward movement.
8. A pipe cutter adapted to cut a pipe in a well by rotation, and comprising relatively movable parts, one of which is rotatable, means for gripping the pipe to be cut and effective to hold one of said parts stationary, an upwardly and outwardly, inside, tapering face on the stationary part, a wedge-shaped slip mounted in the stationary part on said face and movable downwardly and inwardly by gravity and upwardly and outwardly and having inside threads, said rotatable part having external threads arranged to engage the slip threads and to be disengaged therefrom by the rotation of the rotatable part to permit the downward movement of said rotatable part upon disconnection of the threads, a cutter on one part, means for actuating the cutter outwardly into cutting relation with the pipe upon such downward movement, said slip being movable upwardly and outwardly upon upward movement of the rotatable part to permit the inter-engagement of said threads.
9. In a pipe cutter, an outside sleeve having openings, radial gripping members fitted through some of said openings and extending out beyond the sleeve, means for limiting the outward movement of the gripping members, yieldable seats on which the gripping members are seated, radially movable slip jaws fitted through the other of said openings and projecting out beyond the sleeve and means for limiting the outward movement of the slip jaws.
10. A pipe cutter adapted to cut by rotation in a well and comprising a tubular cutter body, a tubular mandrel extended beneath the body, said body having vertical side slots above the mandrel, cutters in said slots whose upper ends are pivoted and whose lower ends are formed with outwardly directed bits, means normally retaining said bits retracted, a guide on the lower end of the mandrel, cutter actuators on the mandrel beneath, and adapted to expand the cutters, a jaw expander having a downwardly tapering face and located on the mandrel beneath the actuators, means for connecting said expander and actuators to permit their relative rotation, a tubular extension on the expander which fits closely over the mandrel, a sleeve around said extension whose lower end has a releasable connection with the guide, radial gripping members working through the sleeve, a liner in the sleeve, yieldable seats between the gripping members and liner normally holding the gripping members outwardly and slip jaws, around the expander and mounted on the sleeve.
11. In a pipe cutter, an outside sleeve having openings, radial gripping members fitted through some of said openings and extending out beyond the sleeve, radially movable slip jaws fitted through other of said openings and extending out beyond the sleeve, means for limiting the outward movement of the gripping members and slip jaws, a liner in the sleeve, yieldable seats between the liner and the gripping members and slip jaws respectively.
12. A pipe cutter adapted to cut by rotation in a pipe in a well and comprising a tubular cutter body having vertical seats, a tubular mandrel depending from the body, cutters pivotally mounted in said seats whose lower ends are provided with outwardly directed bits and inside beveled faces, a wedge ring on the mandrel beneath the cutters formed with cutter actuators, means preventing the rotation of the ring relative to the mandrel, a tubular jaw expander on the mandrel having an upwardly flared face, means for rotatably connecting the expander

with the wedge ring, a tubular extension depending from the expander around the mandrel, a sleeve around the extension, a liner in the sleeve, outwardly movable slips in the sleeve, means 5 normally holding said slips in inner, or active position, gripping members on the sleeve, yieldable means between the gripping members and the liner normally holding said gripping members in outer position, a guide on the lower end 10 of the mandrel, said guide and slips having inter-

meshing threads shaped to effect the expansion of the slips and engagement of the threads upon a longitudinal movement of the mandrel and guide relative to the sleeve in one direction and to be disconnected by rotation of the mandrel 5 and guide relative to the sleeve and slip jaws mounted on the sleeve and arranged to be expanded by said expander upon release of the guide from the sleeve.

WALTER L. CHURCH. 10
